UNITED STATES PATENT OFFICE

HARRY D. LEVINE, OF BROOKLYN, AND ANDREW RADEEFF, OF NEW YORK, N. Y., AS-
SIGNORS, BY MESNE ASSIGNMENTS, TO HARRY D. LEVINE, OF NEW YORK, N. Y.

MEASURING DISPENSER

Application filed September 11, 1928. Serial No. 305,251.

The main object of this invention is to provide a measuring dispenser for such condiments as sugar or the like, and the primary purpose is the construction which will lend 5 itself to a high sanitary standard and permit its molding and manufacture with facility.

Another object of the invention is to provide a dispenser which measures and pours a given quantity of granulated sugar at a tilting of the hand. The device is comprised of two members which may be mutually secured to each other and are divisible to permit thorough cleansing of the parts.

15 The above and other objects will become apparent in the description below in which characters of reference refer to like-named parts in the drawing.

Referring briefly to the drawing, Figure 1-20 is a longitudinal sectional elevational view of the measuring dispenser.

Figure 2 is a top plan view of the dispenser.

Figure 3 is a sectional elevational view of the dispenser measuring unit.

25 Referring in detail to the drawing, the numeral 10 indicates the circular wall of the container which holds the sugar. This wall at its upper encircling edge is provided with helical threads 11 which are engaged by the
30 threaded rim 12 of a flanged and convex cap 13 which closes the upper end of the container. The lower end of the container has an inverted hemi-spherical bottom 14 unitary therewith and at the position where the bottom merges with the wall 10 helical external threads 15 are formed. On the bottom 14 a nipple 16 is formed which projects downwardly from its outer surface in which a tapering aperture 17 is provided. Said aperture
35 communicates with the chamber 18 of the container in which the sugar or other con-
40 diment is captured.

The lower hemi-spherical end of the container is secured in the bowl 19 of the body 45 20 of the measuring unit. The latter is provided with internal helical threads 21 at its upper open end. The bowl-like body is supported and rests on a flanged base 22. The base of the body has a hemi-spherical pocket 50 23 formed therein. This pocket is located

directly below the tapering aperture 17 when the container is secured on the bowl. A curved channel 24 communicating with the pocket 23 is formed in the bowl of the dispenser and extends to the upper edge of the bowl having located at its upper extremity a delivery spout 25.

The chamber 18 of the container is filled with sugar or similar condiment by removing the cap 13. This filling may be done either with the container separate from or secured to the bowl. The dispenser is made of two units so that the device may be readily manufactured and also for sanitary reasons to enable the user to thoroughly clean the pocket and channel. After the container is filled it is inverted with the nipple 16 upmost and the bowl 20 is secured in place thereon.

In use the dispenser rests on the base 22. Sugar or other condiment passes from the chamber 18 of the container and spills through the aperture 17 into the pocket 23 until the latter is filled. This pocket measures a given quantity of condiment. By tilting the dispenser so that the spout lies lower-most, the condiment will slide down the curved channel 24 and will be delivered thru the open spout 25 to the place desired. 75

It is to be noted that certain changes in form and construction may be made without departing from the spirit and scope of the invention.

We claim:

1. In a dispenser, a substantially cylindrical container, adapted to receive a closure cap, a curved bottom on said container having an aperture therein, a similarly curved bowl receiving and removably engaging the bottom of said container, said bowl having a measuring pocket formed beneath said aperture and a discharge channel communicating with the pocket, said channel extending to the upper edge of the bowl, and a delivery spout formed by the termination at its upper extremity of said discharge channel. 99

2. In a dispenser, a substantially cylindrical container adapted to receive a closure cap, a substantially hemi-spherical bottom on said container having a tapering aperture at its axis, a similarly-shaped bowl receiv-

ing and removably engaging the bottom of said container, said bowl having a measuring pocket formed beneath said aperture and a discharge channel communicating with the pocket, said channel extending to the upper edge of the bowl, and a delivery spout formed by the termination at its upper extremity of said discharge channel.

5 In testimony whereof we affix our signatures.

10 **HARRY D. LEVINE.**
ANDREW RADEEFF.
